UNITED STATES PATENT OFFICE.

GEORGE E. DOUGHTY, OF NEW YORK, N. Y.

MANIFOLD SALES-BOOK.

SPECIFICATION forming part of Letters Patent No. 637,094, dated November 14, 1899.

Application filed February 8, 1899. Serial No. 704,877. (No model.)

To all whom it may concern:

Be it known that I, GEORGE E. DOUGHTY, of New York, in the county of New York, in the State of New York, have invented new and useful Improvements in Manifold Sales-Books, of which the following, taken in connection with the accompanying drawings, is a full, clear, and exact description.

The object of my invention is to arrange the parts of a memorandum-book so that the original leaf and the transfer-sheet are normally in position for receiving and transferring the memorandum to the copy-leaf; and to this end the invention consists in a manifold memorandum-book, a series of bound original leaves, a series of continuous leaves having their connected ends clamped to a suitable back, but with the free end of the topmost duplicate leaf detached and two transfer-sheets interposed between the two series of leaves and fastened at opposite ends, one of the transfer-sheets extending between the bottom original leaf and the topmost duplicate leaf and the other extended between the duplicate and triplicate leaves.

A further object of my invention is to adapt a duplicating continuous-leaf memorandum-book to be converted into a triplicating-book; and to this end it consists in a memorandum-book having a block of bound single leaves superposed upon the block of continuous leaves and a semicarbon or transfer sheet fastened between the two blocks of leaves with its back next to the bottom single leaf and its face contiguous to the top continuous leaf, whereby a memorandum written upon the bottom single leaf is transferred to the top continuous leaf and to the subjacent continuous leaf, and the triplicate leaves can be torn out without displacing the transfer-sheets.

To this end my invention consists in the combination, with the cover or base, the pile of duplicates and triplicates folded in zigzag form upon the base, a spring-clamp to hold one end of the pile to the base, a spring-holder to retain the other end of the pile, and a carbon-sheet attached by one end to the spring-clamp, of a spring-binder permanently secured to the said holder, a pile of original sheets confined at one end by the said binder, and a carbon-sheet secured to the said binder below the pile of originals; and my invention

consists in certain other combinations of parts hereinafter described, and more specifically set forth in the claims. 55

In the drawings hereto annexed and forming a part of this specification, Figure 1 is a top view of my improved book with the cover opened. Fig. 2 is a side edge view of the same. Fig. 3 is a side edge view of the book 60 with the cover open and the originals thrown back upon the cover, the position they would occupy when the book is in use. Fig. 4 is an enlarged diagrammatic side edge view of a portion of the book and illustrates clearly the 65 relative position and arrangement of the leaves of the book when in position to receive the writing on the original; and Figs. 5, 6, and 7 are diagrammatic views of the structure, illustrating the operation of the same. 70

In the accompanying drawings, A designates a number of memorandum-leaves piled up and arranged to form a block pad or tablet, and for convenience of reference numbered consecutively from the top to the bottom leaf. The block is placed upon a back or one side of a cover A' and fastened thereto by means of a device that will permit the top leaf (and in some instances, as will be shown presently, the two topmost leaves) to be detached or torn off without displacing the leaf immediately below. On top of the block A another block of memorandum-leaves B is superposed. These leaves are bound together at one end *a* and perforated transversely parallel to the bound end or on line 1, so that they can be readily torn off and leave a stub. This block B is wholly separate and distinct from the block A, and it is held in position with its leaves parallel to the block A and its bound end immediately above an end of the block A by any suitable means, as hereinafter described. The leaves of the block B are numbered consecutively, beginning at the bottom, the order of the numbering being 80 thus the reverse of that of the leaves of block A. A semicarbon or transfer sheet D is placed at the bottom of block B with its end fastened to the bound end of said block or otherwise secured so that the sheet will lie under the 85 bottom leaf *b* of the block. The back of this sheet, which has no transfer-surface, is next to the bottom leaf of the block, while its coated face lies in contact with the top leaf *d* of block 90 95 100

A. Hence a memorandum written on the bottom leaf of block B is duplicated by the transfer-sheet D on another leaf *d*, that has no connection with block B—that is, the topmost leaf of block A.

The above description applies more particularly to an arrangement for making duplicate copies of a memorandum; but as my invention is peculiarly adapted to the making 10 of triplicate copies I will now describe its application to a triplicate memorandum-book. For this purpose I prefer to make the block A of a series of sets of leaves formed in a continuous strip or web of paper folded successively and alternately in opposite directions 15 in zigzag fashion and with transverse perforations on the lines of folding to facilitate the separating of the leaves when desired. This block of continuous leaves is placed upon a 20 stiff-back plate A', which may form one side of a cover. Each set consists of two contiguous leaves *d e*, bearing the same number, and the leaves are folded so that the back of the first leaf of each set will lie on the face of the 25 second leaf of the set throughout the block. This arrangement of the leaves of a duplicate memorandum-book is old and well known; but in adapting it to my system the two leaves forming each set are used to receive 30 the duplicate and triplicate memorandum instead of the original and duplicate as heretofore.

Both ends of the block A are fastened to the back or cover by means of self-adjusting 35 clamps *x y*, that permit the folded ends of the top leaves to be pulled out without disturbing the leaves below them. A semicarbon transfer-sheet E has one end fastened to the clamp *x* and extends thence between the 40 top leaf *d* and its counterpart *e*, the end of the top leaf next to the clamp *x* being free and lying over the clamp. The block B, which is made up of single leaves bound together at one end, is superposed upon the block A, and 45 its bound end *a* is connected with a holder *y'*, mounted on clamp *y*, that holds the lower end of the block *a*, preferably. A semicarbon or transfer sheet D is placed under the bottom leaf *b* of the pad B and has one end fastened 50 to the bound end of the block or to the holder, if preferred, and extends under the bottom leaf *b*, its uncoated back being contiguous to the said leaf and its coated face lying on top of the duplicate *d*, forming part of the block A.

55 The leaves of the blocks A B are substantially conterminous; but the transfer-sheet D is shorter than these leaves. Thus the ends of the leaves lie in contact with each other, and they can be grasped to pull them off without injury to the transfer-sheet between, which is intended to slip out when the leaves are drawn away from the blocks.

60 The leaves of block B receive the original written memorandum, and they are numbered from the bottom to the top, consecutively, in this respect being counterparts of the successive sets of leaves in the block A, which, how-

ever, are numbered downward, as heretofore stated.

The memorandum-blocks, being made up 70 and arranged as described and shown, are connected with a back or one side of a cover by means of suitable clamps *x y y'*, the two former holding the connected ends of the continuous leaves of block A, so that the ends of the topmost set can be pulled out without carrying with them the ends of the subjacent set and the latter arranged for holding the bound end and stub of the block B. The transfer-sheet D lies between the bottom leaf *b* of 80 block B and the top leaf *d* of block A, and transfer-sheet E lies between the top leaf *d* and its next or connected counterpart leaf of the block A.

Thus arranged the operation is as follows: 85 All the leaves of the block B except the last or bottom leaf *b* are turned back, leaving the surface of leaf *b* exposed. The memorandum being written on this is transferred by the carbon-sheets to the duplicate leaf *d* and triplicate leaf *e*. These leaves *b d* are next pulled upward and away from the clamp *y* and stub of pad B, respectively, by grasping their free ends *f f'*, and by a sidewise or tearing motion the leaf *b* is torn off the stub and the connected ends of leaves *d e* are drawn away from the clamp, the said leaves remaining connected. (See Fig. 6.) At this stage the transfer-sheet D remains between the leaves *b d*, and transfer-sheet E lies on top of leaf *e*, as shown in Fig. 6. By continuing to pull the leaves *b d* away from the pad they reach the positions indicated by the broken lines in Fig. 7, the transfer-leaf E being turned backward by the leaf *e*, while transfer-sheet 100 D slips from between leaves *b d* and falls down over top leaf *d* of the next or fresh set of duplicate and triplicate leaves of block A, as indicated by the broken lines. By further pulling on the leaves *b d* the connected 105 ends *g* of the leaf *e* of the first set and the leaf *d* of the fresh set are drawn from under the clamp *x*, and the several leaves *b d e* assume the position shown in solid lines, Fig. 7. It will be observed that the leaf *e* by the 110 last movement was drawn from under transfer-leaf E, the end of which passed under leaf *d*, while transfer-leaf D was drawn upward on top of leaf *d* of the fresh set. A further slight movement upward or backward of the 115 leaves *b d e* carries the latter leaf out of the way of the transfer-sheet E, which falls down on top of the fresh triplicate leaf *e* of the next set. The first leaf *e* is next torn off from the leaf *d* of the fresh set at *g*, whereupon 120 the latter leaf drops down and lies on top of the transfer-sheet E, while the transfer-leaf D falls with it on the top of the leaf *d*, and when the fresh bottom leaf *b* of the pad B is 125 turned over on top of the transfer-leaf D the several leaves are in position to receive another memorandum. By this mode of manipulating the leaves the several triplicate copies are quickly and easily withdrawn from 130

the two blocks without touching the transfer-sheets with the fingers or displacing them from their fastenings, and the transfer-sheets fall back into their respective positions automatically and rearrange themselves when the leaves have been pulled away from the blocks and torn off also without being touched. These duplicates and triplicates *d* and *e* are held on the leaf or back *A'* of the cover at 5 one end by means of a clamping-plate *x*, extending transversely across the outer or upper ends thereof and secured to and supported upon the free ends of parallel spring arms or rods *F* extending obliquely along the sides of 10 the pile or tablet, the body of which arms lies in the said back between the center and lower end thereof, and are held therein by any suitable and well-known means to give to the wire the necessary torsional strain for im- 15 parting a pressure to the clamping-plate *x*, which by its yielding pressure in the direction of the back holds the remaining slips as the others are removed. The opposite or lower end of the pile is also secured under a 20 yielding spring-pressure by means of a holder *y*, the said holder having parallel arms *G* similar to the arms or rods *F* supporting the clamping-plate, and secured, preferably, in the same manner to the back as the arms *F*, such holder 25 30 exerting a yielding pressure upon the lower end of the pile, which, while it permits the ready withdrawal of the slips from under it, at the same time holds the remaining sheets in position against displacement, the yielding pressure being exerted at all times, regardless of the thickness or height of the pile. The clamping-plate *x* has its ends formed into eyes *f''*, as usual, and for the purpose of securing to it the carbon-sheet *E* there is also 35 40 secured upon said arms the well-known hinged binding-plate *f'''*.

Having described my invention, what I claim as new, and desire to secure by Letters Patent, is—

45 1. In a manifold memorandum-book, a semicarbon transfer-sheet interposed between two separate and distinct blocks of paper, one of which is made up of single leaves, and the other of continuous leaves in sets, the said 50 transfer-sheet fastened at one end with its back next to the bottom leaf of the upper block, and its face next to the top leaf of the under block, and a second transfer-sheet fastened by one end and extended between the 55 top leaf of the lower block and its counterpart leaf, whereby an original memorandum written on the bottom leaf of the upper block is transferred to the top leaf and its counterpart of the lower block, substantially as 60 specified.

2. In a manifold memorandum-book, a series of continuous duplicate and triplicate leaves formed in a continuous strip and folded in zigzag fashion, having the connected ends 65 clamped and the upper end of the topmost leaf free, a transfer-sheet interposed between the

duplicate and triplicate sheets, and having its upper end fastened at a point adjacent to the free end of the topmost duplicate leaf, a series of bound original leaves superimposed on the continuous leaves with the bound end clamped at the lower end of the book, and a transfer-sheet having one end attached under the bound end of the original leaves and extended between the bottom of original leaf 75 and the topmost duplicate leaf, substantially as specified.

3. In a manifold memorandum-book, a series of original leaves and a transfer-sheet placed under the same with its back in contact with the bottom leaf—the original leaves and transfer-sheet being bound and fastened at the same end of the book, a series of duplicate and triplicate leaves formed in a continuous strip and folded zigzag fashion, the connected ends being clamped at the end of the book and the end of the topmost duplicate leaf opposite the bound ends of the original leaves and transfer-sheet, free, and a transfer-sheet interposed between the duplicate and triplicate leaves and having its end adjacent to the free end of the duplicate leaf fastened to the book, substantially as specified.

4. In a manifold memorandum-book, a series of bound original leaves, a series of continuous leaves having their connected ends clamped to a suitable back but with the free end of the topmost duplicate leaf detached, and two transfer-sheets interposed between the two series of leaves and fastened at opposite ends, one of the transfer-sheets extending between the bottom original leaf and the topmost duplicate leaf, and the other extended between the duplicate and triplicate leaves, substantially as specified.

5. In a manifold sales-book, the combination with the back, the pile of duplicate and triplicate sheets folded in zigzag form upon the back, the sheets being of substantially the same size as the back and perforated at the folds, a clamp extending transversely across one end of the pile, spring-arms extending from the ends of the clamp obliquely along the sides of the pile to the back, a holder extending across the other end of the said pile, spring-arms extending from the ends of the holder obliquely along the sides of the pile to or near the center of the back, a C-shaped binder on the holder, a pile of sheets held at one end by the binder, and a carbon-sheet below the latter pile and held by the binder, substantially as described and shown.

6. In a manifold sales-book, the combination with the back, the pile of duplicate and triplicate sheets folded in zigzag form upon the back, the sheets being of substantially the same size as the back and perforated at the folds, a clamp extending transversely across one end of the pile, spring-arms extending from the ends of the clamp obliquely along the sides of the pile to the back, a carbon-

sheet attached at one end to the clamp, a holder extending across the other end of the said pile, spring-arms extending from the ends of the holder obliquely along the sides of the pile to or near the center of the back, a C-shaped binder on the holder, a pile of sheets held at one end by the binder, and a carbon-sheet below the latter pile and held by the binder, both of said carbon-sheets having only

their lower sides faced with carbon, substantially as described and shown.

In testimony whereof I have hereunto signed my name.
